UNITED STATES PATENT OFFICE.

CHARLES H. CLARK, OF CRAFTON, PENNSYLVANIA, ASSIGNOR TO CLARK CAR COMPANY, OF PITTSBURGH, PENNSYLVANIA, A CORPORATION OF NEW JERSEY.

DUMP-CAR.

1,136,315.

Specification of Letters Patent. Patented Apr. 20, 1915.

Application filed July 15, 1908. Serial No. 443,654.

To all whom it may concern:

Be it known that I, CHARLES H. CLARK, a resident of Crafton, in the county of Allegheny and State of Pennsylvania, have invented certain new and useful Improvements in Dump-Cars, of which the following is a specification.

One object of this invention is to provide an improved construction wherein a car of given width and height clearances provides a load-carrying space of maximum cross-sectional area. The length of car necessary for a load of given cubical amount is thus minimized, and results in an economy of material as the length of the longitudinal members of the car body decrease with an increase in the cross-section of load space.

The invention relates primarily to dump cars, and the feature of load-space of maximum cross-sectional area is attained, in part, by an improved under-frame so constructed that the body or hopper is sustained in a relatively low position. The result is that a substantial portion of the load is in and below the draft plane, *i.e.*, the plane of the draft beams, resulting in a low center of gravity which is highly desirable.

A further feature of the invention, and one quite essential to the attainment of maximum load cross-section for a given height clearance, is the arrangement of bottom doors which operate in such manner as to occupy no appreciable part of the vertical clearance space when opening and closing. In the present adaptation, the doors operate in a substantially horizontal plane, the doors being inclined in accordance with the angle of friction of the material hauled, and remaining inclined while moving bodily when opening and closing. Provision is also had for slightly increasing the inclination of the doors while opening, determined by operating conditions. A feature of the door construction is the provision of means for preventing the discharge of material through the crack that may form between the doors when closed.

Another feature of the invention is the improved door-operating mechanism which has direct shifting connection with the doors, avoiding chains, links, and other intermediate parts liable to uneven wear, disorder and ineffective operation.

It is characteristic of the present embodiment of direct-connected operating mechanism that the shifting connection is maintained and operates in a horizontal plane, the advantage of which is the simplicity of mechanism required and the facility with which the oppositely moving doors are operated in perfect unison.

ment of direct-connected operating mechanism that the shifting connection is maintained and operates in a horizontal plane, the advantage of which is the simplicity of mechanism required and the facility with which the oppositely moving doors are operated in perfect unison.

A further feature of the invention is the arrangement of the draft beams with reference to the longitudinal beams of the frame, the latter being connected by transverse beams to which, in turn, the draft beams are secured, whereby the moment strains of the transverse beams are availed of to form an appreciable yielding or flexible connection, and to that extent compensate the draft forces and cause the frame to withstand the same more effectively than in those constructions wherein the draft and longitudinal beams are so directly connected as to preclude compensation.

The best friction draft gears for car couplers will not compensate more than 180,000 pounds; but it has been found that the draft forces run as high as twice this amount when cars in motion come in contact with cars standing still, and at other times during the movement of long trains. This has resulted in high repair cost for draft sills, which my invention greatly reduces by increasing the flexible resistance of the car frame, and using the frame against the higher draft forces as a part of the yielding draft rig.

Still a further object is to provide an improved chord for the top edge of the car, the same being designed to economically resist the compression strains due to supporting the major portion of the load on the side girders. Also, the improved chord resists the wear and prevents damage usually resulting from clamping the car when in a car dumping machine, and prevents injury when loading with a steam shovel, the shovel dipper frequently striking the top chord.

In the accompanying drawings, Figure 1 is a vertical cross-section of a car constructed in accordance with the invention, the section being on line 1-1 of Fig. 2. Fig. 2 is a longitudinal section of a portion of the car, taken on line 2-2 of Fig. 1. Fig. 3 is a sectional plan, taken on line 2-3 of Fig. 2. Fig. 4 is a section, on a larger scale, of the internally threaded sleeve and its

connection with the door. Fig. 5 is a similar view, enlarged, of the meeting edges of the doors.

In adapting the invention to a dump car, 5 as here shown, the longitudinal beams 2 of the under-frame are spaced apart to admit therebetween hoppers 3. While the side beams do in effect extend as far as the body bolster 5, the main beams 2 preferably stop 10 short of the latter and are provided with extension members 2' which in reality form parts of the side beams.

The extremities of beam extensions 2' are connected by the transverse beam 4, which 15 I term the bolster beam, as it forms the bottom cover-plate for bolster 5, in the present adaptation said beam being of greater area than the usual bottom cover-plate. Spaced inwardly and toward the 20 hopper from beam 4 a distance to afford clearance for the wheels W is a second transverse beam 6, which also connects beam extensions 2', preferably where they join beams 2. Transverse beams 4 and 6 are 25 connected by longitudinal plate 7, over which extends draft beams 8, the latter secured to said plate and to beams 4 and 6, as shown.

It is desirable that the car frame shall as 30 far as possible compensate the draft forces, but such result is not possible where the draft and longitudinal beams are so connected that the full force of the tension and compression strains are of necessity transmitted from one to the other. With the construction herein proposed, the moment strains of the transverse beams 4 and 6 are availed of, and to that extent the rigidity of 35 the connection between the draft and longitudinal beams is relaxed and the strains compensated.

The dumping feature of the car is here embodied in two oppositely moving doors 10 disposed longitudinally of the car and 45 which when closed meet in a line intersecting the car center, with the outer edges of the doors underlapping the sloping side walls 11 of the hopper. The doors are preferably inclined in accordance with the angle 50 of friction of the material to be transported, and provision is had for holding the doors inclined during their movement bodily while opening and closing. The doors are thus sustained by the transverse track-like members 12, secured to the under portion of the car body at each end of the pair of doors, the end 10' of each door being provided with a wheel 13 secured near the upper or outer edge of the door, and a wheel 14 near its inner or lower edge, said wheels being movable on the track members 12, as shown.

A characteristic of the invention is the movement of the doors bodily in a substantially horizontal plane, also the horizontally operating door actuating mecha-

nism presently to be described. As such mechanism is by preference connected to the upper or outer portion of the door, provision is had for that portion of the door moving in a horizontal plane. To this end, 70 the outer portions 15 of tracks 12 are substantially horizontal. In some instances, it is desirable to slightly increase the inclination of the doors as they open, and to accomplish this the inner portions of the tracks 75 or supports 12 are inclined from the center outwardly and downwardly, as indicated at 16, these being the portions of the tracks traversed by wheels 14. Thus it will be seen that while wheels 13 move back and forth 80 in a horizontal plane, wheels 14 drop slightly as the doors open and to that extent increase the inclination of the latter. While track 12, considered as a whole from one side of the car to the other, has the inclined portions 85 16 embodied in an elongated substantially U-shaped depression of the track, such construction is incidental and not essential.

In the transportation of comminuted materials, iron ore for example, there is considerable waste through the crack, however small, between the doors. I overcome this by providing an automatic seal, which consists of a channel-like extension on one of the doors which underlaps the other door. 90 The channel is wide enough to cover a crack of any usual proportions, and the hollow of the channel is upward and is of such depth that the angle of repose of the material which flows therein from the crack will be 95 wholly within the channel. Such angle is indicated by the line A—A, Fig. 5. Channel 17 is preferably formed on the lower edge of the downward door-extension 18, and the other door has a similar extension 100 19 which moves in the vertical plane of channel 17 when the doors close. The channel may be variously formed, and while extensions 18 and 19 are preferred they are 105 not essential.

The mechanism for operating the doors is connected directly thereto and transmits the necessary movements preferably in a horizontal plane. This arrangement provides for a direct application of the power, avoiding chains, links and other intermediate connections liable to wear and disorder, and occupies space of relatively small area. This operating feature may be embodied in mechanisms of various forms. That here shown consists of horizontal screw shafts 115 20 journaled transversely in the frame adjacent to supports 12, and adapted to travel on each shaft e internally screw-threaded sleeves 21, secured to the door ends coincident with wheels 13. It will be understood that the opposite ends of each shaft 20 are threaded reversely, so that the doors move outwardly when the shafts are rotated in one direction and inward for the oppo- 120 125 130

site direction. The lateral or outward pressure of the load on the inclined doors exerts force of such an amount that comparatively slight additional force, applied when dumping the car, is necessary to open the doors. The pitch of the threads on the shaft is such as to prevent the load pressure alone from opening the doors. The result is that the doors will remain in any intermediate position they may be put, and can never open accidentally. A further advantage of the improved construction is that it is unnecessary to raise the doors to close them, as in many types of doors, which results in a great saving of labor. The opposite bodily movable doors are thus mechanically controlled throughout their opening and closing movements. They can neither open nor close suddenly or with a slam. The manual power in the present embodiment imparted through screw shafts 20, is always sufficient to either open the doors or close them, substantially the same amount of power being required for each operation. The two shafts 20 for each set of doors are provided with sprockets 22, from which sprocket chains 23 lead to the short shaft 24 provided with hand wheel 25, whereby the shafts necessarily operate in unison. It will be understood however that the shafts may be variously operated. The opposite sides of the car body, for a distance upward from the sloping hopper sides 11, are vertical, as indicated at 26, and these vertical lines indicate the maximum width clearance of the car. I am enabled to accomplish this by reinforcing the upper portions of the walls by stiffeners 27 secured to the inner faces thereof and extending downward preferably a short distance over the inclined hopper walls 11. These stiffeners thus overlap stiffeners 28 for said inclined walls which are arranged on the outer surfaces thereof, there being ample room for the same, and also by this means the sloping surfaces are left free and unobstructed so that there is no opportunity for the material to hang or clog within the hopper when dumping. The top chord of the car, constituting the top edge thereof consists of the channel 30 of inverted U-section which embraces the whole top edge of the body. A chord of this section presents an economical distribution of metal for resisting all the strains, including those due to supporting the load on the side girders. Also, this form of chord resists the wear and compression strains incident to clamping the car in a car dumping machine. This operation, as is well known, frequently results in injuring the car due to the top chord not being sufficiently strong to resist the compression strains placed thereon at such time. A chord of this form also, protects the top

edge from injury due to the dragging thereover of the dipper of a steam shovel, a source of injury to which this class of cars is constantly subjected.

I am aware that various channel sections have been used for top chords; but the chord here shown is curved throughout its exposed portion so that all of the exposed metal is in compression as an arch when resisting pressure from the clamps of a car dumping machine, or impact from a steam shovel dipper.

I claim:—

1. A pair of opposite bodily movable doors for a dump car inclined when closed, each door rotatable about an axis located between the upper and lower edges of the door, means for causing said axes to move horizontally with the doors as they open and close, and means for causing the doors to move simultaneously.

2. An inclined bodily movable door mounted to roll without raising its center of gravity, and means for holding the door at any position through which it moves.

3. An inclined bodily movable door for a dump car mounted to lower its center of gravity while opening, and mechanism for holding the door at any position through which it moves.

4. A dump car door movable bodily, means for simultaneously moving opposite edges of the door upwardly and downwardly respectively while moving bodily, and horizontally shifting means connected to the door for moving it bodily.

5. A dump car door movable bodily, means for simultaneously moving opposite edges of the door upwardly and downwardly respectively, a screw shaft, a sleeve traveling on the shaft, and an operative connection between the sleeve and door for effecting the bodily movement of the latter.

6. A door for a dump car movable bodily, screw shafts arranged transversely of the door, sleeves on the shafts pivotally connected to the door, and means for turning the door on said pivotal connections during the movement of the sleeves on the shafts.

7. A door for dump cars movable bodily, horizontal screw shafts, sleeves on the shafts, pivotal connections between the sleeves and door, and means for turning the door on said pivotal connections during the horizontal movement of the sleeves on the shafts.

8. A bottom for car hoppers consisting of horizontally movable doors inclined when closed and closing together at their inner edges, means for varying the inclination of the doors while opening and closing, and mechanically controlled horizontally shifting door-actuating means.

9. A bottom for car hoppers consisting of inclined bodily movable doors, means for

- varying the inclination of the doors while opening and closing, and mechanically controlled door actuating means having shifting connections with the doors.
5. 10. A bottom for car hoppers consisting of oppositely inclined bodily movable doors meeting at their lowermost edges, means common to the doors for moving them bodily toward and from each other, and means for increasing the inclination of the doors as they move apart.
11. A bottom for car hoppers consisting of oppositely inclined bodily movable doors meeting at their lowermost edges, means common to the doors for moving them bodily away from each other, and means for increasing the inclination of the doors as they move apart.
12. A bottom for car hoppers consisting of oppositely inclined doors meeting at their lowermost edges, means movable in a horizontal plane for moving the doors away from each other, and means for increasing the inclination of the doors as they separate.
13. A bottom for car hoppers consisting of laterally movable oppositely inclined doors, supports, wheels carried by the doors and engaging the supports, the supports and wheels being arranged to maintain the doors constantly inclined, a screw shaft, and threaded sleeves connected to the doors and embracing the shafts.
14. A bottom for car hoppers consisting of oppositely inclined doors, supports for the doors, the outer portions of the supports disposed horizontally and their inner portions inclined, wheels on the doors for the horizontal and inclined portions of the supports, and door actuating means.
15. A bottom for car hoppers consisting of oppositely inclined doors, supports for the doors, the outer portions of the supports disposed horizontally and their inner portions inclined, wheels on the doors for the horizontal and inclined portions of the supports, door actuating means having shifting connections with the doors.
16. A bottom for car hoppers consisting of oppositely inclined doors meeting at their lowermost edges and movable laterally in opposite directions, supports having horizontal portions coincident with the outer parts of the doors and depressed portions coincident with the inner portions of the doors, threaded sleeves carried by the portions of the doors which traverse the horizontal parts of the supports, and screw shafts on which the sleeves are mounted.
17. In a bottom for car hoppers, a bodily movable door inclined when closed, supports over which the higher and lower portions of the door move and arranged to increase the inclination of the door while opening, and actuating means connected to the door coincident with the uppermost supports.
18. A pair of roller-supported bodily movable doors for a dump car inclined when closed, and mounted to increase their inclination while rolling open, without raising the center of gravity of either door, and means common to the two doors for rolling them simultaneously when opening and when closing.
- In testimony whereof I affix my signature in presence of two witnesses.
